UNITED STATES PATENT OFFICE.

CLARENCE S. JACKSON OF NEW YORK, N. Y., ASSIGNOR TO NATIONAL BOTTLE CAP COMPANY OF NEW YORK, N. Y., A CORPORATION OF NEW YORK.

BOTTLE-REFILL-PREVENTING DEVICE.

1,118,423.

Specification of Letters Patent.

Patented Nov. 24, 1914.

Application filed July 24, 1913. Serial No. 780,888.

To all whom it may concern:

Be it known that I, CLARENCE S. JACKSON, a citizen of the United States, residing in New York city, in the county of New York and State of New York, have invented certain new and useful Improvements in Bottle-Refill-Preventing Devices, of which the following is a specification.

The objects of my invention are to provide an effective, simple, cheap and readily-applied, automatically-closing stopper, designed to be permanently attached to bottles and like vessels, which will permit their contents to be poured without delay or inconvenience, but will prevent them from being re-filled.

In the drawings, Figure 1 is a section through the neck of an upright bottle and my stopper connected therewith, Fig. 2 a corresponding end view, Fig. 3 a side view of the stopper shell, Fig. 4 an outer and Fig. 5 an inner end view. Figs. 6 and 7 are functional sections, Fig. 6 illustrating the act of pouring and Fig. 7 the automatic closure 25 of the stopper when the bottle is held at any angle between vertical and horizontal. Fig. 8 is a sectional view of a preferred form.

To prepare a bottle 1 for my stopper, the neck is formed with an exterior attachment 30 shoulder, 2, and terminates in a nozzle, 3, whose inner walls contract to form a valve seat 4, which may be of any contour, and is illustrated as an annular plane. I provide a valve shell 5, preferably made of porcelain, and comprising a cylindro-conoidal axial body 6 containing an outwardly-closed tubular valve chamber 7, whose inner surface merges into the conical inner surface, 8, of a conoidal closure, 9, and on 35 whose cylindrical exterior staggered baffles 10 are formed, which fit the nozzle 3 and whose staggered openings 11, form a sinuous discharge passage 12; and a mouthpiece 13 adapted for a cork and united with the axial body 6 by arms 14 and provided with an outer shoulder 15 for engagement with a suitable tubular spun-metal clamp 16, which 45 clamps the shell 5 firmly to the bottle and makes a tight joint between them.

In the valve chamber 7, I locate a valve 50 17, illustrated as a short tube, and exterior thereto a weight, preferably a glass ball 18. In order that the valve may not be fluid-bound it is necessary to provide a way communicating the outer part of the valve

chamber, either with the atmosphere or with the bottle, which might be done by channeling the exterior of the valve or perforating the wall of the chamber. Both these methods are objectionable. If the wall were 60 perforated, a tube could be applied to the hole and the valve thereby sucked off its seat 4. While there is not room to channel the valve without too greatly reducing the width of the valve seat. Moreover, experience proves that the tubular valve moves more freely and seats with less effort than any other because the total volume contained within the bottle, valve chamber and valve bore is constant and the valve can be 70 moved to and from its seat without causing any flow whatever through the exterior passage. This is a highly important characteristic when the valve has to be sensitive as in such uses.

The operation of my stopper is as follows: When the bottle is held horizontal (Fig. 7), or inclined between horizontal and upright, the ball 18 rests on the conical surface 8 and gravity causes it to have a closing 80 component which becomes greater as the dip of the bottle becomes less, becomes maximum when it is upright and which presses the valve 17 to its seat 4. When the bottle is tilted in the act of pouring, and the conical surface 8 upon which the ball rests, declines beyond the horizontal, the ball no longer exerts its pressure on the valve, and the valve falls forward by gravity. The fluid then passes through the lower part of 90 the sinuous discharge passage, while the air enters through the upper level of said passage, as illustrated in Fig. 6. When the bottle is brought back nearly to or to horizontal, the ball rolls back upon the surface 95 8 against the valve 17, presses it to its seat, and seals the bottle against the entry of liquid.

In Fig. 8 is disclosed a modified form of the foregoing described stopper, the change 100 in structure, however, not affecting the principles described, the said changes being made for the purpose of permitting cheap and easy manufacture when the device is to be made of porcelain. Like numbers refer 105 to like parts in the above noted figure, and it will be seen that in the preferred form the upper pouring portion 13 is a separate piece from the conoidal body 6, the said body being flat at its top portion instead of 110

rounded, as shown in Fig. 1. The pouring portion 13 is also provided with a flat baffle member 13' which is connected by arms 19 to the outer shell thereof and with the said portion 13, when in position, retains the conoidal member 6 in operative position through adhesion to the said portion 13', the two said members being placed together and baked while in this position, thereby 10 practically forming an integral member. The only advantage in the above noted construction over that disclosed in Fig. 1 is in the purpose of cheapening the molds and to insure economy in the manufacture of the 15 article.

I claim as new and desire to protect by Letters Patent:

1. In combination with a bottle neck and a valve seat therein, a fixed, axial, cup-shaped body containing an outwardly closed 20 conical chamber, expanding inwardly into a cylindrical chamber, a tubular valve adapted to coact with said seat, a spherical weight

adapted when the bottle is substantially horizontal to rest upon the conical wall of 25 said chamber and against the valve, to close it, and sinuous passages circumferential relatively to said body.

2. In combination with a bottle neck and a valve seat therein, a fixed, axial, cup-shaped body containing an outwardly closed 30 conical chamber, expanding inwardly into a cylindrical chamber, a plurality of staggered, interrupted annular separators on said body adapted to center it in the neck 35 and form therewith sinuous passages with staggered baffles, a valve adapted to coact with said seat, a spherical weight adapted when the bottle is substantially horizontal to rest upon the conical wall of said chamber and against the valve, to close it. 40

CLARENCE S. JACKSON.
